UNITED STATES PATENT OFFICE

2,116,404

ELECTRICAL INDUCTION APPARATUS

Vincent M. Montainger, Pittsfield, Mass., assignor
to General Electric Company, a corporation
of New York

Application March 23, 1937, Serial No. 132,528

5 Claims. (Cl. 175—362)

The invention relates to electrical induction apparatus, such as a transformer or reactor, wherein a winding leg of a magnetic core is surrounded by a winding or windings. The invention is furthermore particularly concerned with apparatus having high voltage windings of the disk coil type. Such a high voltage winding must be effectively insulated from the winding leg of the core and from any low voltage winding which it may surround, and suitable provision must be made for dissipating heat from the winding to prevent excessive temperatures. The necessary insulation is usually provided by one or more insulating cylinders between the high voltage windings and the 5 winding leg of the magnetic core. The disk coils forming the high voltage winding are usually spaced from each other and from the insulating cylinder which they surround to provide passageways for an insulating and cooling liquid in which the apparatus is immersed. It has been found that if the voltage of the winding in such an arrangement is increased to the point of breakdown, corona will first appear and breakdown will first 10 take place along the inner edges of the disk coils where they are spaced a short distance from the insulating cylinder.

The general object of the invention is to provide an improved arrangement of high voltage winding with its insulating cylinder wherein a 15 much higher voltage is necessary before corona and breakdown will occur.

The invention will be better understood from the following description taken in connection with the accompanying drawing in which Fig. 1 is a 20 simple partially diagrammatic view of a core type transformer having windings which may be arranged in accordance with the invention; Fig. 2 is an enlarged view of a portion of the transformer, the windings in this view being shown 25 partly in section; Fig. 3 is a sectional view on the line 3—3 of Fig. 2; Fig. 4 shows a detail on the line 4—4 of Fig. 2, and Fig. 5 shows a modified form of the invention.

Like reference characters indicate similar parts 30 of the different figures of the drawing.

The transformer shown in the drawing includes a magnetic core 18 having two winding legs 11 surrounded by high voltage windings 12 and low voltage windings 13, each low voltage winding 13 being next to its winding leg 11 and surrounded 35 by its high voltage winding 12. Each high voltage winding 12 is insulated from its low voltage winding 13 by two concentric insulating cylinders 14 and 15 which are spaced from each other to provide a duct or passageway 16 for a cooling liquid.

The insulating cylinders 14 and 15 are imperforate and are formed with end flanges 17 and 18 respectively which provide insulation between the ends of the winding and the adjacent yokes 19 of the magnetic core. Suitable spacing strips 5 20 are provided between the insulating cylinders 14 and 15 and between their flanges 17 and 18.

In accordance with the invention the high voltage winding 12 includes a plurality of spaced disk coils 21 with their inner edges in contact 10 with the outer surface of the insulating cylinder 14 which they surround. There is thus no space for cooling liquid between these disk coils 21 and their insulating cylinder 14 so that if any corona 15 starts at all it must start in the solid insulating material of the insulating cylinder 14 instead of in an insulating liquid and it is well known that corona will start much more easily in liquid insulation than in solid insulation. It is, however, not necessary that the disk coils 21 fit so tightly 20 against the insulating cylinder 14 as to exclude all liquid because the dielectric strength of a thin film of insulating liquid is much higher in proportion to its thickness than is that of a thicker 25 layer of such liquid.

The disk coils 21 are maintained in spaced relation by U-shaped spacers 22 and simple spacing strips 23. The winding 12 must of course be held in place under considerable pressure and it is therefore necessary that the spacers 22 and 23 30 be held in alignment to avoid distortion of the individual coils 21. To assure such alignment of the spacers 22 and 23, the insulating cylinder 14 is formed with longitudinal grooves 24 in its outer surface and the inner ends of the spacers extend 35 and fit into these grooves. The spacers 22 extend along opposite faces of the coils 21 and around the inner edges where they fit into the grooves 24. The spacing strips 23 are disposed between 40 the U-shaped spacers 22 and their inner ends also extend into the grooves 24. The spacing strips 23 may of course be of any desired thickness depending upon the desired spacing of the coils 21 or they may be omitted if not needed.

The insulating liquid in which the transformer 45 may be immersed will have free access to the upper and lower faces and to the outer edges of each of the coils 21 so as to absorb heat from these coils to improve the circulation of the liquid. To improve the circulation of the 50 liquid so that it may carry away the heat more rapidly, alternate coils are formed in two concentric spaced portions so that ducts 25 extend between the upper and lower surfaces of these alternate coils. The cooling liquid may thus flow 55

into the space below each of these ducts 25, through the duct and out of the winding through the space above the duct. These ducts 25 should be as near as possible to the inner edges of the 5 coils so that the liquid will flow in contact with as much as possible of the surfaces of the coils. The liquid flows of course not only along the surfaces of those coils which are provided with the ducts 25 but also along the surfaces of the 10 other coils not so provided with ducts and which are therefore solid, and thus the heat is dissipated effectively from all of the coils even though the cooling liquid is substantially excluded from the inner edges of the coils next to 15 the insulating cylinder upon which they are supported.

In the modified form of the invention shown in Fig. 5, alternate solid coils are wound tightly over the insulating cylinder 14 and with their 20 inner edges in contact therewith. The ducts 25 associated with the other coils, however, are provided by spacing the inner edges of the other coils from the cylinder 14 instead of forming these ducts through these coils near their inner 25 edges. The spacing of the inner edges of alternate coils from the cylinder 14 to provide the ducts 25 is permissible because of the fact that the adjacent coils are in contact with the insulating cylinder and definitely establish the potential distribution along the cylinder at frequent intervals so that the voltage across the ducts 25 will not be sufficient to produce corona.

The invention has been explained by describing and illustrating a particular transformer constructed in accordance therewith, but it will be apparent that changes may be made without departing from the spirit of the invention and the scope of the appended claims.

What I claim as new and desire to secure by Letters Patent of the United States, is,—

1. Electrical induction apparatus including an insulating cylinder with longitudinal grooves in its surface, and a plurality of spaced disk coils 5 in contact with said surface, alternate coils having ducts near said cylinder and the other coils being solid.

2. Electrical induction apparatus including an insulating cylinder with longitudinal grooves in 10 its outer surface, and spaced disk coils surrounding said cylinder with their inner edges in contact with the cylinder, alternate coils having ducts near their inner edges, and the other coils being solid.

3. Electrical induction apparatus including an insulating cylinder with longitudinal grooves in its outer surface, spaced disk coils surrounding said cylinder with their inner edges in contact with the cylinder, and spacers between said coils 20 and extending into said grooves, alternate coils having ducts near their inner edges, and the other coils being solid.

4. Electrical induction apparatus including an imperforate insulating cylinder, a plurality of 25 spaced disk coils, alternate coils being solid and each having an edge in contact with the cylinder, there being a duct associated with each of the other coils and connecting the adjacent spaces near said cylinder.

5. Electrical induction apparatus including an imperforate insulating cylinder, a plurality of 30 spaced disk coils surrounding said cylinder, alternate coils being solid and each having its inner edge in contact with the cylinder, there being a 35 duct associated with each of the other coils and connecting the adjacent spaces near said cylinder.

VINCENT M. MONTSINGER.
